UNITED STATES PATENT OFFICE.

FRANK M. PEREZ, OF BROOKLYN, NEW YORK, ASSIGNOR, BY MESNE ASSIGNMENTS, TO
DAVID BRODY, OF NEW YORK, N. Y.

DISPLAY BOX OR CARTON.

1,338,394.

Specification of Letters Patent. Patented Apr. 27, 1920.

Application filed December 18, 1916. Serial No. 136,780.

To all whom it may concern:

Be it known that I, FRANK M. PEREZ, a citizen of the United States, residing at Brooklyn, in the county of Kings and State 5 of New York, have invented certain new and useful Improvements in Display Boxes or Cartons, of which the following is a specification.

My invention relates to an improvement 10 in boxes or cartons; particularly boxes or cartons made of cardboard, and capable of serving the double purpose of containing merchandise and displaying the same when the articles, goods, etc., in such boxes or cartons are to be put upon view.

An object of my invention is to provide 15 a box or carton having an especially designed lid or cover adapted to close up the box entirely when the contents thereof are merely to be stored; to support the same in the most advantageous position for display 20 when the dealer wishes to exhibit the whole of the contents of the box or carton to prospective purchasers. The cover may also 25 have a display portion to attract attention to the box or carton, and this display portion may be shaped so as to permit inspection of the contents without the cover being moved to open position.

Another object of my invention is to provide 30 a box or carton, which is simple in construction; but which can be easily and cheaply made; yet be sufficiently strong and compact to enable it to serve efficiently the 35 purposes for which it is intended.

The above and other objects and advantages 40 of my invention are clearly set forth in the following specification, taken in connection with the accompanying drawings; and the novel features of my invention are 45 precisely defined in the appended claims. This disclosure, however, is to be taken as explanatory only, and embodiments other than those actually shown herein may be 50 sorted to in practice; within the scope and spirit of my invention; as indicated by the terms in which the claims are expressed and the variations in the wording of the same.

On the drawings:—

Figure 1 is a plan view of a blank, out 55 of which my improved box or carton can be made;

Fig. 2 is a front elevation of the box when the parts are all in display position;

Fig. 3 is a side elevation of the box in the 55 same position as Fig. 2;

Fig. 4 is a rear elevation of the box in the same position as Fig. 2;

Fig. 5 is a side view of my improved box 60 with the parts thereof in closed position;

Fig. 6 illustrates a modified blank to be 65 used in the making of my improved box or carton;

Fig. 7 is a rear elevation of a box constructed from the blank having the modifications shown in Fig. 6; with the parts of the box all in position to display the contents;

Fig. 7^a is a side elevation of a box constructed from the blank shown in Fig. 6 70 with the parts in open position.

Fig. 8 is a view in perspective showing a modified box or carton;

Fig. 9 is a section taken on the line 9—9 75 in Fig. 3;

Fig. 10 is a sectional view taken on the line 10—10 in Fig. 6; showing a detail as the same will appear when the blank is folded; and

Figs. 11 and 12 are detail views showing 80 another manner in which the various portions of the blank shown in Figs. 1 and 6 can be joined together when the blank is shaped to give my improved box or carton its final form.

The same numerals indicate the same 85 parts throughout.

I wish to state at the outset that in the following description I shall portray a 90 box or carton which is made out of a single blank of cardboard, according to my invention.

This form and method of manufacturing the same are preferable because I am thereby enabled to make up my improved box or carton in knockdown or fold- 95

ing form, so that the wholesaler can purchase the blanks for my improved boxes or cartons in large quantities; and finish constructing the boxes himself by shaping these cartons or blanks, as required, in his factory.

But I do not wish to be limited to a 100 box or carton made according to my invention, out of a single blank of suitable material, or in knockdown form; as I may obviously construct my boxes out of separate pieces of material, cut in the required size

and shape, and glue or otherwise fasten the same together.

Referring to my invention as illustrated in Figs. 2, 3, 5 and 8; I show a receptacle, constituting my improved box or carton consisting of a body 1 and a hinged lid or cover 2; provided with a movable section 3; the parts mentioned appearing best in Fig. 8, which is a perspective view of the same. The lid or cover is intended to close the box entirely, as in Fig. 5; or to permit the 10 contents of the box to be seen without having to be moved to open position, as in Fig. 8; this object being gained merely by elevating the section 3. The lid is also adapted to be folded rearward and then forward 15 under the box, as illustrated in Figs. 2 and 3, to support the carton in position to display the contents when the carton is to be placed in a case or upon a counter. This capacity for serving a variety of purposes 20 is one of the distinctive features of my invention.

In order to make my improved box or carton in the simplest or best fashion and at the same time produce an efficient construction, I preferably have recourse to a 25 foldable blank, such as is shown in Fig. 1. This blank may be of cardboard or other suitable material; and the line of demarcation between the parts out of which is 30 formed the body 1 and the lid 2 is indicated by the numeral 4. This line and all other broken lines on the blank represent score lines; that is, lines made by scoring or cutting the cardboard on one face only, but 35 not through it; while the continuous lines extending within the periphery of the blank in Fig. 1 indicate lines along which the cardboard is cut through entirely. When the different portions of the blank are all folded 40 to give the box or carton its final shape, the line 4, which runs across the blank, will be at the rear edge of the body 1; the part of the blank below the line 4 in Fig. 1 being for making the body, and the part 45 of the blank above this line being for the lid 2.

I shall deal first with the part of the blank below the transverse line 4. This comprises a central portion 5, which will 50 constitute the bottom of the finished box; and below and above the portion 5, in Fig. 1, are transverse portions 6 and 7 for forming the front and back of the box, respectively. These portions are marked off from 55 the portion 5 by the score lines 8; and both the portion 6 and the portion 7 have terminal extensions 9 at their opposite ends. At the sides of the portion 5 are longitudinal portions 10, for forming the sides of the 60 completed box; and each of these portions 10 will have an extension 11, of the same length as the sides of the box, and of the same width as the height of the sides. Score lines 8, running lengthwise of the blank, 65 mark off the extensions 9 from the portions

6 and 7, and the portions 10 from the portion 5; and similar score lines 8 mark off the portions 10 from the extensions 11.

To give the body its shape, the portions 6 and 7 are bent or folded up at right angles 70 to the portion 5, about the score lines 8 between them and this portion; and the extensions 9 at each side of the box are bent or folded, about the score lines 8 at their inner ends, toward each other, and over the 75 portions 10. The portions 10 are then bent up about the score lines 8 between them and the portion 5, against the outer faces of the extensions 9; that is, the faces of these extensions which are under those seen by the 80 observer in Fig. 1; and the extensions 11 are turned inward and downward. By folding the extensions 11 along the score lines 8 between them and the portions 10 down into the box, the portions 9 at each side are held 85 between the portions 10 and extensions 11, as best illustrated in Figs. 2 and 9, particularly the latter. In order to maintain the folded portions 6, 7, 9, 10 and 11 of the blank in their proper positions, I may provide 90 the extensions 11 with wide tongues 12, projecting a short distance beyond the outer edges of these extensions; and at the sides of the bottom 5 I may locate short and wide tongues 13; cutting these tongues 95 in the bottom 5 so that their free ends will coincide with the score lines 8 between the bottom and the portions 10. When the extensions 11 are turned down into the box, over the extensions 9, the tongues 12 and 13 100 at each side are caused to engage; the tongues 12 passing through the bottom of the box; and the tongues 13 may be bent either downward and outward slightly, or upward and inward to a slight degree, as 105 illustrated in Fig. 9. By this method, the box is easy and cheap to make, and is yet strong, compact and durable.

To make the lid or cover out of the part of the blank above the line 4 in Fig. 1, I 110 provide this part with two portions 14, for forming the sides of the cover 2. The lid will in effect be hinged to the body along the score line 4; and the portions 14 may be conceived as beginning at the opposite or 115 free end of the lid and extending along each side toward the hinged end; widening as they go. They are marked off from the top of the lid, in which is located the movable section 3, by longitudinal score lines 8; and 120 their smaller ends, adjacent the free end of the lid, are provided with terminal extensions 15, connected to the portions 14, but cut free from the part of the blank between them. The blank between these extensions 125 15 is scored transversely, so as to delineate three portions, indicated at 16, 17 and 18, and having substantially equal widths; and the score line 8 between the portions 18 and 130 the section 3 is continued across the blank 135

between the portions 14 and extensions 15. To give the lid its shape, the portions 14 are first bent up at right angles, about the score lines 8 between them and the section 3, in the same manner as the portions 6 and 7. The extensions 15 are then folded toward each other, about the score line above referred to, across the portions 16, 17 and 18; and the latter are then bent up by folding them as a unit about the score line 8 nearest to the section 3. Thus the section 18 will be caused to lie against the outer faces of the extensions 15, that is, the faces turned away from the observer in Fig. 1. I 15 next fold the sections 16 and 17 about the score line nearest to the score line last mentioned; thus causing the extensions 15 to be held between the portions 17 and 18, in the manner indicated in Fig. 5, which shows 20 the extensions 15 and the portions 16, 17 and 18 in cross section. The section 16, finally, is bent in the opposite direction outward, so as to lie against the lower face of the top of the cover 2; this face being the one shown in Fig. 1. In this position, it will 25 be secured by a tab 19, which will be bent back to allow the edge of the portion 16 to be passed under it, and then released to engage and hold the portion 16.

30 At their wider ends the portions 14 have extensions 20, for a purpose to be set forth hereinafter. These extensions 20 are marked off from the portions 14 by transverse score lines 8, which are continued inward from both sides of the blank as far as the lateral edges of the section 3. Between these score lines and the line 4 are portions 35 21, of a width equal to the distance between the section 3 and the sections 20, and of a 40 length equal to the width or height of the back 7. I provide the section 3 preferably by cutting through the blank above the line 4, along three sides of this section; leaving it secured to the blank along the fourth side, 45 which coincides with the line 4, so that the section may be moved about this line to either open or shut position. I also cut the extensions 20 free from the blank entirely except along the score lines between them 50 and the portions 14. The score lines 8 between the portions 5 and 10, the portions 6 and 7 and the extensions 9, the edges of the extensions 20 adjacent the portions 21, the score lines 8 along the portions 14, and the 55 edges of the portions 15 adjacent the portions 16, 17 and 18, make one continuous line at each side of the blank from one end to the other.

When the box is closed, the extensions 20 60 will be in the same planes as the portions 14, to which they are connected; and the side portions 14 of the cover 2, with these extensions 20, will fit down over the side portions 10 of the body 1. Hence the box will 65 be sealed. The sections 3 can now be ele-

vated, as in Fig. 8, without moving the lid to open position, to permit the contents of the box to be seen, if desired. To support the box for display, the lid is folded back and down beneath the box, as in Figs. 2, 3 and 4. In this position, the sides 14 present their narrower ends to the front, thus holding up the box at an incline forward; and exhibiting the goods it contains in the most advantageous fashion. In this case, the extensions 20 are bent toward each other, just under the portion 7 of the body 1, to brace the portions 14; and the portions 21, which are of the same length, between the line 4 and the score line 8 above it, as the width 75 or height of the portion 7, will lie against the back of this portion; the cover being bent or folded forward under the body 1 below the portions 21, about the line 8 which, when the blank is laid out flat, as in 80 Fig. 1, runs between the portions 14 and extensions 20 to the display section 3.

When the box is set up as in Fig. 8, a sheet of gelatin or other transparent material may be used to close the opening made 90 by bending up the section 3. The gelatin may be permanently secured to the inner face of the lid around the section 3; or it may be made separate and attached to the outside of the cover in any suitable way to 95 prevent displacement.

If desired, the extensions 20 may be omitted; and so may the section 3. If the movable section of the cover 3 is dispensed with, the score line 8 between the portions 14 and 100 the extensions 20 will be extended entirely across the cover 2. This score line may be caused to run entirely across the cover 2 when the section 3 is present; so that this section may be either used as in Figs. 2, 105 3 and 8, or folded down beneath the box with the portions 14. When present, the section 3 may be given any convenient 110 shape, and the lower face thereof, which will be presented to the front when the section is elevated, will have printed or other matter thereon in accordance with the character of the merchandise in the box or carton.

With the blank shown in Fig. 1, the cover 115 is bent back and down around the line 4, which is at the rear edge of the body 1; and then forward around the line 8 running from the side edges of the section 3 out between the portions 14 and extensions 20; 120 this line being, as above stated, located about the middle of the section 3. In the blank shown in Fig. 6, however, the cover is intended to be bent back and down, not about the line 4, but about a score line 8 just above 125 this line 4. In this case, the section 3 does not begin at the line 4, along the upper rear edge of the body 1, but at the line 8 just mentioned; and the portions 14, instead of running from the free edge toward the 130

hinged edge of the cover 2 as far as the middle of the section 3 (as in Fig. 1), terminate with their wider ends on a line with the outer or free edge of this section. Hence the portions 21 must be of the same length as the section 3; and the length of the portions 21 must be approximately the same as the distance between the score line 8 along the hinged edge of the section 3 and the bottom portion 5. The portions 21 extend from the line 8 at the hinged end of the section to score lines 8 at the free end of the same. This blank also has one or more tabs 19; and one or more tongues 22, cut in the bottom 5 adjacent the score line 8 at the rear thereof. These tongues will extend downward from the back 7 when the box is formed; see Fig. 10; and when the cover 2 is folded under the body 1, these tongues 22 will engage the edge 23 of the opening left by the section when the same is elevated; and prevent the body from sliding forward on the cover 2. When set up for display by means of the cover 2, a box made from the blank in Fig. 6 will appear as in Fig. 7; which shows the same from the rear. Extensions 20 may be provided or dispensed with, according to the user's preference. I may, of course, cut tongues 22 in the bottom 5 of the blank shown on Fig. 1; locating them where they will engage the edge 23 in the cover 2 when the box or carton is set up as in Figs. 2, 3 and 4.

When the blank shown in Fig. 6 is folded to form a box, and the cover turned down under the box to elevate the rear end of the same, the portions 21 will not lie flat against the rear end 7 of the box, and the portion of the lid between the top edge of the rear end 7 and the score line 8, which passes across the cover at the hinged end of the section 3 will not be in line with the rear end 7 of the body 1. Instead, this portion will extend backward a little, and with the section 3 will incline slightly to the rear to about the same extent as the section 3 when the box made out of the blank shown in Fig. 1 is set up in the manner illustrated in Fig. 2. With the parts in these positions, the portions 21 will inclose a small triangular space with the rear end of the box and the portions of the lid or cover between the line 4 and the line 8 which passes across the lid or cover at the hinged end of the section 3. In other words, when the lid is folded under the body 1 and the tongues 22 engage the edge 23, these portions 21 will be caused to exert some tension on the portion of the lid between the score line 8 which passes across the lid at the hinged end of the section 2, and the score line 4 at the hinged end of the lid; and in effect pull the section 3 backward to the required extent.

The facts detailed in the foregoing para-

graph are best illustrated in Fig. 7a of the drawings.

In Figs. 11 and 12, I show another manner of making the box or carton; so as to hold the portions 5, 6, 7 and 10 in proper relative positions; likewise the portions 14, 15, 16, 17 and 18 of the cover 2. I here omit the extensions 9 on the portions 6 and 7; and locate L-shaped slots 24 in these portions at their opposite ends. I provide the portions 10 with extensions 25; and in the edges of these extensions adjacent the portions 6 and 7, I make diagonal cuts 26. From the inner edge of each of these cuts runs a score line 8, diagonally in the other direction back to the edge of the projection 25. These cuts 26 make widening tongues 27; and the aforesaid lines 8 delineate foldable points 28 on these tongues 27. When the points are folded from full line to dotted line position, as indicated in Fig. 11, the tongue is caused to become narrow, instead of wider, toward the portion 6. When the portions of the blank are folded up, the points 28 are folded in this way; and the tongues then passed through the slots 24. After they are through, the points 28 are turned back into the plane of the tongues again; making them wider than the length of the horizontal portions 29 of the slots 24 which they occupy; so that they cannot be withdrawn. This expedient may be adopted for either the portions 6, 7, or 14; though shown in connection with the portion 7 only.

I have asserted above that the extensions 20 may be omitted when they are not wanted. If they are left off, the portions 10 will be provided with slots 30; so that the points or corners of the portions 14 of the cover may be inserted into them when the cover is closed; and hold the cover securely when the box is shut. This point is illustrated in Fig. 8.

The display portion or section 3, in order to be in display position, need only be maintained sufficiently upright to present the advertising matter on its forward face to advantage when the body of the receptacle is supported in display position by the aid of the cover, as herein described.

If desired, I may shape the portion 2 of the blank shown in either Fig. 1 or Fig. 6 so as to cause the extensions 15 to be engaged, to hold the side portions 14 at right angles to the lid, in the same manner as the extensions 9 are engaged by the portions 10 and 11 to hold the portions 6 and 7 at right angles to the bottom 5 of the box or carton. For this purpose I merely dispense with the portion 16; utilizing only the portions 17 and 18 between the extensions 15. When the portions 14 are folded up around the longitudinal score lines 8 and the extensions 15 bent toward each other, the portions 17 and 18 will be folded as before around the trans-

verse score lines 8 to grip the extensions 15 between them, as shown in Fig. 5. To hold the portions 17 and 18 in this position the portion 17 will be provided at its outer edge with one or more tongues, exactly like the tongues 12 at the outer edges of the portions 11; and the lid 2 between the section 3 and the portion 18 will be provided with one or more tongues exactly like the tongues 13. The tabs 19 will therefore be omitted. When the portions 17 and 18 are folded over the extensions 15, the tongues at the outer edge of the portion 17, corresponding with the tongues 12, will be made to engage with the tongues between the portion 18 and the section 3, corresponding to the tongues 13; in the same way as shown in Fig. 9. Furthermore, the tongues at the outer edge of the portion 17 will project through the lid 20 beyond the top or outside face of the same; and when the box is set up, as shown in Figs. 2, 3, 4, 7 and 7^a, the ends of these tongues on the portion 17 can be caused to enter slots in the bottom 5. These tongues will therefore coöperate with the tongues 22 to hold the lid 2 and body 1 in proper relative positions to display the contents of the carton.

It will be understood, of course, from the foregoing, that my improved box or carton, whether made from the blank shown in Fig. 1 or that shown in Fig. 6, can only be maintained in display position by folding the portion of the cover carrying the sides 14 and the end made up of the sections 16, 17 and 18, under the end of the body to which the cover is hinged. In other words, the body of the box could not be supported if the cover is simply turned down at the back of the box and stood vertically on its free end. In such a position, the cover could not bear the weight of the body 1 and the contents for the reason that the portions 21 are not adapted to permit the cover to be utilized in this way.

Having described my invention, what I claim to be new, and desire to secure and protect by Letters Patent of the United States is as follows:—

1. A receptacle comprising a body and a cover therefor, the cover being connected to one end of the body and being provided with a movable section for permitting the contents of the receptacle to be seen without the cover requiring to be moved to open position, said cover being formed to enable it to be folded under the body to support the latter in position with said end elevated to display the contents of same.

2. A receptacle comprising a body and a cover therefor, the cover being provided with a movable section for permitting the contents of the receptacle to be seen without the cover requiring to be moved to open position, said cover being formed to enable it to be folded rearward and under the body

to support the latter in position to display the contents thereof, and simultaneously elevate said section into position to present to view the lower face of the same.

3. A receptacle comprising a blank 70 folded to provide a body and a cover, the latter being formed to enable it to be folded downward at one end of the body and under the latter to permit the bottom of the body to rest thereon and to elevate said end and 75 support the body in position to display the contents of the same.

4. A receptacle comprising a body and a cover therefor, the latter being hinged to the body and having sides maintained in 80 fixed relation to the top of the cover and widening away from the free end of the cover, the cover being adapted to be disposed so that the sides will be below the body to support the same at an incline for 85 display.

5. A receptacle comprising a body and a cover therefor, the latter being hinged to the rear end of the body and being transversely foldable to enable it to be turned 90 under the body to permit the bottom of the body to rest thereon and to elevate said end and support the body in position to display the contents of same.

6. A receptacle comprising a body and a 95 cover therefor, the cover being hinged to the body and having side portions which widen away from the free end of said cover, said cover being transversely foldable adjacent the wider ends of said side portions to enable it to be turned under the body to support the latter in position to display the contents of same.

7. A receptacle comprising a single blank bent to form a body and a cover hinged to 105 one end of the body, the cover being formed to enable it to be lifted and folded along a transverse line between its ends to enable the end of the cover to be carried below the plane of the bottom of the body to permit 110 the bottom to rest thereon, the body then being capable of being supported by the aid of the cover, with said end elevated, to display the contents.

8. A receptacle comprising a body and a 115 cover hinged to one end thereof, said cover being adapted to be turned downward and under the body to permit the bottom of the body to rest thereon and elevate said end of the body, and having sides to be disposed 120 below the body and support the same at an incline for display.

9. A receptacle comprising a body and a cover therefor, said cover being hinged to one end of the body along one edge of said 125 end, said cover being adapted to be turned about said edge to extend across said end and to be folded about a transverse line under the body to permit the bottom of the body to rest thereon and elevate said end 130

- of the body, said cover having sides between said line and said free end to be disposed below the body and support the same at an incline for display.
- 5 10. A receptacle comprising a body and a cover hinged to one end of the body along an edge of said end, said cover being adapted to be folded about a line adjacent said edge to extend across said end, and being further adapted to be folded about a line adjacent its free end under said body to elevate said end of the body, said cover having sides adjacent its free end to be disposed below the body to support the same at an incline for display.
- 10 15. 11. A receptacle comprising a body and a cover hinged to one end thereof, said cover being adapted to be turned downward and under the body, and having sides to be disposed below the body and support the same at an incline for display, said cover bearing a display section adapted to maintain a position above the body when the cover is turned down under the body.
- 20 25. 12. A receptacle comprising a body and a cover therefor, said cover being hinged to one end of the body along one edge of said end, said cover being adapted to be turned about said edge to extend across said end and to be folded about a transverse line under the body, said cover having sides between said line and said free end to be disposed below the body and support the same at an incline for display, said cover bearing a display section adapted to be maintained in a position above the body when the cover is folded under the body.
- 30 35. 13. A receptacle comprising a body and a cover hinged to one end of the body along an edge of said end, said cover being adapted to be folded about a line adjacent said edge to extend across said end, and being further adapted to be folded about a line adjacent its free end under said body, said cover having sides adjacent its free end to be disposed below the body to support the same at an incline for display, said cover bearing a display section adapted to maintain a display position when the cover is folded under said body.
- 40 45. 14. A receptacle comprising a body and a cover hinged to one end of the body along an edge of said end, said cover having tapering sides, the narrow ends of said sides being located at the free end of the cover and the wide ends being remote from the opposite end of the cover, said cover being adapted to be turned about a line adjacent the said edge to extend across said end of the body and being adapted to be folded about a transverse line at said wide ends of the sides, under said body, whereby the sides will support the body at an incline for display, said cover bearing a display section adapted to be maintained in a display position when the cover is folded downward and under the body.
- 50 55. 15. A receptacle comprising a body and a cover having hinged connection with the body at a point remote from the front end of the latter, the cover having side portions and an end portion and being movable about said hinged connection with the body either to close the body or to be carried into po-
- a cover therefor, said cover being hinged to one end of the body along one edge of said end, said cover having tapering sides, the narrow ends of said sides being at the free end of the cover and the wide ends of said sides being remote from the opposite end, said cover being adapted to be turned about said edge to extend across said end of the body and be folded about a transverse line at the wide ends of the sides, under the body, whereby the sides will support the body at an incline for display, said cover bearing a display section adapted to be maintained in a display position when the cover is folded downward and under the body.
- 60 65. 16. A receptacle comprising a body and a cover hinged to one end of the body along an edge of said end, said cover having tapering sides, the narrow ends of said sides being located at the free end of the cover and the wide ends being remote from the opposite end of the cover, said cover being adapted to be folded about a line adjacent the said edge to extend across said end of the body and being adapted to be folded about a transverse line at said wide ends of the sides, under said body, whereby the sides will support the body at an incline for display, said cover bearing a display section adapted to be maintained in a display position when the cover is folded downward and under the body.
- 70 75. 17. A receptacle comprising a body and a cover hinged to one end of the body, the cover bearing a display portion, the cover being adapted to be turned so as to extend across the plane of the bottom of the body, the body then being capable of being supported by the aid of the cover, with said end elevated, in display position, the display portion also being adapted to maintain display position when the body is in display position, and means for enabling the cover and the body to be secured to each other when the body is in display position.
- 80 85. 18. A receptacle comprising a body and a cover hinged thereto, the cover bearing a display portion, the cover being adapted to be turned so as to extend across the plane of the bottom of the body, the body then being capable of being supported by the aid of the cover in display position, the display portion also being adapted to be maintained in a display position when the body is in display position, the cover also having a portion which is adapted to be folded under the body when the latter is in display position.
- 90 95. 19. A receptacle comprising a body and a cover having hinged connection with the body at a point remote from the front end of the latter, the cover having side portions and an end portion and being movable about said hinged connection with the body either to close the body or to be carried into po-

sition to support the latter with its rear end elevated to display its contents, said end of the cover when the body is thus elevated being located beneath the body remote 5 from the front end of the latter, and the bottom of the body then resting on a part of said cover.

20. A receptacle comprising a body and a cover having hinged connection with the body at a point remote from the front end of the latter, the cover having side portions and an end portion and being movable about said hinged connection with the body either to close the body or to be carried into

position to support the latter with its rear 15 end elevated to display its contents, said end of the cover when the body is thus elevated being located beneath the body remote from the front end of the latter, and the bottom of the body then resting on a part of said 20 cover, said receptacle also having a display section adapted to be maintained in a position above the body adjacent the rear end of the latter when the body is thus elevated.

In testimony whereof, I have signed my 25 name to this specification this sixth day of December, 1916.

FRANK M. PEREZ.
